UNITED STATES PATENT OFFICE.

JOHN E. MUHLFELD, OF SCARSDALE, AND GEORGE W. CLENDON, OF BROOKLYN, NEW YORK, ASSIGNORS TO ECONOMY DEVICES CORPORATION, OF NEW YORK, N. Y., A CORPORATION OF NEW YORK.

SAFETY APERTURE-CLOSURE.

1,261,952.

Specification of Letters Patent. Patented Apr. 9, 1918.

Application filed September 7, 1915. Serial No. 49,184.

To all whom it may concern:

Be it known that we, JOHN E. MUHLFELD of Scarsdale, county of New York, and State of New York; and GEORGE W. CLENDON, of the borough of Brooklyn, county of Queens, State of New York, have invented certain new and useful Improvements in Safety Aperture-Closures, of which the following is a specification.

10 This invention relates to a safety aperture closure or device for containers of liquid, gaseous or other material, such, for example, as steam engine valve chests, steam boilers and the like.

15 One of the primary objects of our invention is to provide a simple, effective and inexpensive safety closure of the character specified. Another of the objects of our invention is the provision of an improved detachable safety closure device for closing an aperture in a container of fluid or other similar material, so arranged with reference to the means for detachably securing the closure as to secure a tight joint. Our invention further contemplates the provision of an improved detachable closure device of the character specified having safety means whereby, in the event of failure of the means for detachably securing the closure, the closure is prevented from blowing off of the container. Our invention also comprises the provision of an improved closure device whereby the joint between the closure and the container may be located back of means used to removably connect the container to an adjacent construction, and also the utilization of such means as a safety device, preventing the closure from blowing off of the container in the event of failure of the means for securing the closure in place.

The foregoing, together with such other objects as may hereinafter appear or are incident to our invention, we obtain by means of a construction, a preferred embodiment of which we have illustrated in the accompanying drawings wherein:

Figure 1 is a longitudinal section through a steam engine valve chest, showing our invention applied thereto; Fig. 2 is a front end elevation of Fig. 1; Fig. 3 is a sectional detail taken on the line III—III of Fig. 1; Fig. 4 is a front end elevation of a valve chest embodying a modification of our invention; Fig. 5 is a section taken on the line

V—V of Fig. 4; and Fig. 6 is a detailed section of another modification of the invention.

Inasmuch as our invention is particularly advantageous in connection with steam engine valve chests, it has been shown in the drawings and will be described in the specification as applied thereto. In order that our invention may be better understood, a brief description will be made of the valve chest.

Referring particularly to Figs. 1 and 2, it will be seen that we have shown a portion of a cylinder 1, which is provided with a flat valve face 1^a having induction and eduction port openings 2—2, intermediate 70 which is an exhaust port opening 3. The induction and eduction port openings 2—2 form the terminals of the induction and eduction ports 2^a which lead to opposite ends of the cylinder 1. The port opening 75 3 is a terminal of the exhaust port 3^a which communicates with an exhaust pipe (not shown). A segmental or D-shaped valve chamber 4, open at the ends, is detachably secured to the valve face by any preferred means, there being interposed between the valve face and the valve chamber a plurality of gaskets 6, which may be of any preferred type but which are shown in the drawings in the form of joint wires. Removably mounted in the valve chamber 4 is an open ended, suitably ported, cylindrical bushing 7 in which the piston distribution valve reciprocates. This piston valve comprises two cylindrical heads 8—8 provided with suitable packing rings, and an intermediate spool 8^a, the heads and spool being rigidly connected by means of the bolt 8^b. The stem for operating the valve is indicated by the numeral 9. Inclosing the valve mechanism is a valve chest 10 which is preferably cast integral and which is detachably secured to the cylinder 1 by means of a plurality of studs 11 and nuts 11^a, a suitable gasket 10^a being interposed between the valve chest and the valve chest seat formed on the cylinder. The valve chest mechanism just described is what is known as the universal valve chest by means of which it is possible to substitute for the ordinary slide valve mechanism a piston distribution valve, without the substitution of new parts.

Heretofore it has been customary to cast the valve chest as an integral unit, and although peep-holes have been provided therein, the valve chest was so constructed that it was necessary to remove it bodily from the cylinder when it was desired to replace or adjust any of the valve parts located therein. We propose to provide an opening in the valve chest of a size sufficient to remove the valve parts for purposes of repair or replacement and to close such opening by our improved cover or closure device. With this in view, the valve chest 10 is provided at its forward end with an aperture 12 having a shoulder 12^a. The closure for this opening preferably comprises a cylindrical member 13 having a flange 13^a and a shoulder or offset portion 13^b corresponding to the shoulder 12^a in the aperture or opening 12. The gasket 13^c, preferably joint wire, is interposed between the shoulders 12^a and 13^b. The closure is detachably secured in position by means of a plurality of studs 14 and nuts 14^a. Formed in the cylindrical portion of the closure are vertical holes 15, preferably two in number, such holes being arranged so that a pair of the studs 11, by means of which the valve chest 10 is detachably secured to the cylinder 1, may be passed therethrough. This construction forms a simple, convenient, and inexpensive safety device preventing the cover or closure from blowing off of the valve chest in the event that the studs 14 or nuts 14^a fail. It will thus be seen that the studs 11 which pass through the closure perform a double function, namely, they have their normal function of securing the valve chest 10 to the cylinder 1, and they form a safety retaining means for the closure. No additional parts are thus required.

Inasmuch as the closure must have movement relative to the safety holding means, in order that a tight joint between the closure and the valve chest may at all times be secured, the diameter of the holes 15 is made larger than that of the studs 11 which pass therethrough. In order to prevent leakage through the openings 15 and around the studs 11, the aperture 12 and the closure are so formed that the shoulders 12^a and 13^b are located to the rear of the studs 11; that is to say, the joint for the closure is located between the safety holding means and the pressure cavity of the valve chest proper. It will be seen that by this improved construction a steam tight joint for the closure is secured while at the same time the safety means is so arranged that the nuts 14^a may be freely drawn up to tighten the joint, as may be required. As hereinbefore pointed out, this safety closure device is simple, effective and inexpensive, and requires but a minimum number of

parts. The arrangement shown permits of the ready renewal of the gasket or other packing means employed.

In the modification shown in Figs. 4 and 5, our invention is also illustrated as applied to a steam engine valve chest. This construction, however, differs from that previously described in that the aperture or opening 12 in the valve chest and the cover or closure 13 are of rectangular shape, and that the cover is provided with a plurality of slots 15^c instead of the holes 15 as shown in the construction of Figs. 1, 2 and 3. These slots permit movement of the cover relative to the studs 11 so that the joint may be tightened whenever necessary.

In the construction shown in Fig. 6 the opening 12 in the valve chest 10 is tapered and threaded and the closure 13 is in the form of a tapered threaded plug having a squared end 16. A single hole 17 is formed in the plug for the reception of the stud 11, which in this case acts not only as a safety element but also as a means for preventing the cover 13 from working loose.

It will be seen from the foregoing that our invention comprises among other things the provision of an improved closure device for containers of steam, liquid or other material, which closure device is readily detachable for purposes of inspection, repair or replacement; and which is provided with safety means adapted to retain the closure in the event of the failure of the attaching means. While our invention is shown as applied to the valve chest of a locomotive, it is not limited to this use, and changes may be made without departing from the spirit of the invention.

We claim:

1. The combination of a pressure container having an opening, of bolts for detachably securing said pressure container to an adjacent structure, an end plate for said opening, and means for detachably securing said end plate in position, said end plate being so arranged relative to the pressure container that the bolts which attach said pressure container to the adjacent structure serve as safety retaining means in the event of failure of the means for detachably securing the end plate in position.

2. The combination of a pressure container having an orifice, means for detachably fastening the pressure container to an adjacent structure, and an end plate for said orifice, the means for detachably securing the pressure container to the adjacent structure being located outside of the inner face of the end plate thereby serving as a retaining means therefor.

3. The combination of a pressure container having an orifice, of means for detachably securing the pressure container to an adjacent structure, a closure member for

said orifice, certain of said fastening means being located outside of the inner face of the said closure member to act as a retaining means therefor, and a packing between the 5 pressure container and said closure member located intermediate the said fastening means and the pressure chamber of the container.

4. The combination of a pressure container 10 having an orifice, of means for detachably securing said pressure container to an adjacent structure, a closure member for said orifice, and means for detachably securing said closure member to the pressure container, a 15 part of said means for detachably fastening the pressure container to the adjacent structure having coöperative relation with the closure member to retain the same in position in the event of the failure of the 20 means for detachably fastening the closure member to the container.

5. The combination of a pressure container 25 having an orifice, of means for detachably fastening said pressure container to an adjacent structure, a closure member for said orifice, said fastening means having lost motion connection with said closure member, and means for adjusting the position of the closure member with reference to the pressure 30 container.

6. The combination of a pressure container 35 having an orifice, of a closure member for said orifice, and means for detachably securing said pressure container to an adjacent structure, said means coöperating with said

closure member to act as a retaining means therefor.

7. The combination of a pressure container having an orifice, of a closure member for said orifice, means for detachably securing 40 said closure member to the pressure container, and means for detachably fastening the pressure container to an adjacent structure having coöperative relation with the closure member to retain the same in position in the event of the failure of the means for detachably fastening the closure member to the pressure container.

8. The combination of a pressure container having an orifice, of a closure member 50 for said orifice, means for detachably securing said closure member to the pressure container, means for detachably fastening the pressure container to an adjacent structure having coöperative relation with the 55 closure member to retain the same in position in the event of the failure of the means for detachably fastening the closure member to the pressure container, a packing for said closure member located intermediate the 60 pressure container and means for detachably fastening the pressure container to the adjacent structure.

In testimony whereof we have hereunto signed our names.

JOHN E. MUHLFELD.
GEORGE W. CLENDON.
